UNITED STATES PATENT OFFICE

MARCUS C. STEESE, OF HAMBURG, NEW YORK

FURNACE

Application filed December 13, 1920. Serial No. 430,194.

This invention relates to open hearth furnaces, and more particularly to the fluid passageways and the control of fluids passing therethrough, and also to means for obtaining more efficient combustion of various fuels.

5 The present construction of an open hearth furnace consists of the usual hearth, combustion chamber and port block arrangement, which is standard for most all types of open hearth furnaces.

10 A furnace using producer gas has in addition usually one uptake for gas on each end and its gas port, and two uptakes for air on each end and air ports. The lower ends of these uptakes terminate, respectively, in a gas slag pocket and air slag pocket on each end, which are in turn connected to gas checkers and air checkers, respectively, which are in turn connected to the stack through gas and air reversing valves, both ends of the furnace being the same.

Generally, in furnaces using natural gas or coke oven gas and tar, another construction is resorted to in connection with the uptakes, in which the furnace is constructed with one large uptake extending across each end of the furnace, this terminating at the lower end in one slag pocket, which in turn is connected with the air regenerator, which 25 in turn is connected to the stack through a reversing valve. This second class of furnaces is sometimes operated by using the standard producer gas furnace and cutting the slag pocket walls out between the slag 30 pockets, making one large chamber, and using both the gas and air regenerators on either end.

A third type of furnace recently developed is similar in construction to a producer gas 40 furnace with the exception that dampers are placed in the four air uptakes with operating mechanism for closing and opening said dampers, and the slag pockets are connected by cutting through the walls.

45 All these types of furnaces are built especially for their respective fuels, and it is a matter of considerable time and expense to change from one fuel to another, the change involving cooling off the furnace and tearing down brickwork, and rebuilding and heat-

ing up the furnace again. Owing to the close connection also between the slag pocket and the checker chambers or regenerators, the function of the slag pocket being to collect the heaviest particles of material coming down the uptakes so that the gas in passing to the checker chambers is as clean as possible, a great deal of dirt collects on top of the checker chambers and decreases the life thereof by either clogging up or depositing a coating 55 on top. There would be advantage gained in this respect if it were possible to provide a settling chamber between the slag pocket and checker or regenerator chamber, where the gases would still drop more of the suspended matter contained therein, and this would materially lengthen the life of the checkers three or four times.

In the first type of furnace, namely, a producer gas furnace, sometimes it becomes advisable to introduce a tar burner or a gas burner within the gas port. This requires considerable time and expense and in this type of furnace it is further quite a problem to arrange the uptakes at either end of the furnace to provide sufficient area for the outgoing gases and waste products, and the life of the furnace is quite often terminated by the burning through of the division walls. There also being two slag pockets of necessarily small comparative size, one or the other will often fill up rapidly, which again terminates the life of the furnace. Accordingly, there is great advantage in constructing a furnace of the second type, namely, a straight gas or tar furnace involving the large unit uptake and the large single slag pocket and the single checker chamber; but this type of furnace would be useless for the burning of producer gas. It is more or less successfully used for tar, coke oven gas and powdered fuels.

80 One object, therefore, of my present invention is to provide an open hearth furnace construction in which all fuels may be efficiently burned interchangeably without change in construction or operation.

85 Another object of this invention is to simplify and improve the uptake construction for open hearth furnaces and to control in a 90 100

novel manner the supply of fluids therethrough and the cooperative action of fuel supply and air supply for properly proportioning and obtaining efficient combustible mixtures.

Another object is to provide a more efficient combustion than is possible at present in the large uptake type of furnace described hereinabove when using coke oven gas, tar or powdered coal.

Another object is to automatically control the total quantity of air in accordance with the supply of fuel.

Another object is to provide for an intimate mixture of fuel and air and a partial combustion of same prior to entering the combustion chamber.

Another object is to accomplish these functions with no additional apparatus, and, as a matter of fact, with less apparatus than is necessary on the present producer gas furnace.

These and other objects are accomplished by means of the arrangements disclosed on the accompanying sheets of drawings, in which—

Figure 1 is a fragmentary longitudinal sectional view of an open hearth furnace embodying my invention;

Figure 2 is a transverse sectional view taken in the plane of line 2—2 of Figure 1;

Figure 3 is a fragmentary longitudinal sectional view of an open hearth furnace embodying a modification of my invention;

Figure 4 is a fragmentary sectional view taken in the plane of line 4—4 of Figure 3;

Figure 5 is a transverse sectional view of the open hearth furnace taken in the plane of line 5—5 of Figure 3; and,

Figure 6 is a plan sectional view taken in the plane of line 6—6 of Figure 5.

The various novel features of my invention will be apparent from the following description and drawings and will be particularly pointed out in the appended claims.

Referring first to Figures 1 and 2 of the drawings, it will be noted that I have shown an open hearth furnace having a hearth 10 upon which a bath 11 is supported, there being two ports 12 and 13 leading to the combustion chamber 14. These ports 12 and 13 are in open communication with one large uptake 15 which communicates with a central uptake 16, which in the regular open hearth furnace is the gas uptake, and with two other uptakes 17. It will be understood that these uptakes 16 and 17 are connected with their respective slag pockets 18 and 19, which are connected with the usual checker or regenerator chambers. Transversely

of, and preferably in the middle of, the large uptake 15, I provide a baffle or air trap 20, which preferably is semi-circular in section. This baffle extends through the end wall 21 of the furnace, through the uptake 15 and

65 into a receiving opening in the port block

22. Mounted within the semi-circular baffle 20 and extending through the end wall 21 of the open hearth is a fuel burner 23, which may be of any suitable type and which includes a conduit 24 for the supply of various fuels, such as coke oven gas, natural gas, producer gas, powdered coal and the like, which may be supplied from any suitable source indicated by the pipe 25. If desired, tar may be supplied through the pipe 26. The fuel

supply pipes 24 and 26 are mounted within the casing 27, and in each case the fuel is supplied under a high pressure for inducing a supply of air through the port 12, forming

therein an intimate mixture of gas and air, which undergoes partial combustion within the port, and upon issuing into the chamber 14, the velocity is retarded below the rate of flame propagation, whereupon combustion

takes place completely and at a very high rate. This complete combustion is assisted by an auxiliary or excess supply of air through the port 13, such auxiliary air also

directing the flaming combustible mixture onto the bath, and guiding the direction of movement through the combustion chamber. The air which passes through the port 13 is the excess of the air not induced by the flow of fuel under pressure through port 12, and this excess amount of air is under the control of the furnace operator and regulated

by a valve for admitting air through the regenerator or checker chambers. The total amount of air entering the furnace through the uptake 15 is a result of the thermal head or temperature in the uptake and is controlled by a valve admitting air to the bottom of the regenerators. This air in flowing upwardly, due to its natural head, is divided

by the inducing action of the fuel under pressure, part mixing with the fuel and entering the furnace through the opening 12 and the remainder passing on either side of the baffle 20, reference being had particularly to Figure 2, and entering the furnace through the air port 13. With a fixed amount of air flowing up the air uptake 15, and with the control of the injection of air through port 12, more or less air can be induced through port 12,

and if all of the air were induced through port 12, none would pass on either side of the baffle 20 and enter the furnace through port 13. Therefore, it is possible by means of the air valve 35 below the regenerator and the injection action to control the amount of air

entering through port 12 and the amount of air entering through port 13 within wide limits and easily under the control of the operator.

It is desirable to have a certain quantity of air enter the furnace through port 13 and that amount would be indicated by a certain small pressure evidenced at the rear of port 13. By means of a suitable dia-

phragm construction, which would operate

125

130

electric contacts, a small motor would raise and lower the air valve, which permits air to enter the bottom of the regenerator, the amount of air flowing up uptake 15 would be automatically controlled as the operator would vary the flow of fuel through burner 23, which in turn automatically causes more or less air to be induced from uptake 15 through port 12 into combustion chamber 14.

One form of automatic control referred to hereinabove may take the form of a delicate pressure member, such as swinging damper 28, which operates within a pipe 29 in open communication with the upper end of uptake 15. A contact 30 at the upper end of this damper may electrically engage contacts 31 and 32, which are in the circuit of the propelling motor 33 for actuating any suitable mechanism 34 for raising and lowering the air valve 35, which controls the flow of air to the regenerators, from which said air passes through slag pockets 18 and 19, uptakes 16 and 17, uptake 15, and into the combustion chamber through ports 12 and 13, as hereinabove described. For example, if the pressure in the uptake 15 is above a predetermined value, as set by the furnace operator, the damper 28 will move outwardly and contact 30 engage with contact 31 for moving the valve 35 toward a closed position. On the other hand, if the pressure at the upper end of uptake 15 is below said certain predetermined value, the damper 28 will move inwardly so that contact 30 will engage contact 32 for causing the air valve 35 to be opened a given amount, whereupon additional air will be supplied to the uptake 15.

Referring now to Figures 3 to 6, inclusive, attention is first directed to the fact that instead of providing a plurality of slag pockets, as shown in Figures 1 and 2, a single slag pocket 36 is provided, which is in open communication with one large uptake 37, which extends the full width, or the greater part thereof, of the furnace. This furnace is provided with the usual hearth 38 on which the bath 39 is supported, there being an air intake port 40 connecting the upper end of the uptake 37 with the combustion chamber 41. Introduced across uptake 37 is one or more baffles or air traps 42, which extend through the end wall 43 of the furnace and across uptake 37 and extend into openings in the port block 44. These baffles 42 preferably are semi-circular in section with the open portion downward. The inner or active end of each of the baffles is provided with a throat 45, the function of which will be more fully described hereinafter. Mounted within this baffle and extending through the end wall and partially across the air uptake 37, is a fuel burner 46, the active end of which terminates somewhere within the uptake 37, and arranged so as to be adjustable 65 of its length and transversely within the uptake. The burner is movably supported on pipes 60 and the burner is permitted to move back and forth as a result of the flexible member 61 located at the outer end of the burner in the fuel supply line. The center line of the jet of the burner coincides very closely with the center line of the throat 45. The fuel is supplied to this burner under pressure suitable to perform the necessary function of inducing sufficient air through the throat 45 from uptake 37 to combustion chamber 41 to provide an intimate mixing of fuel and air in throat 45 and partial combustion therein and this mixture upon entering the combustion chamber 41, where the velocity of the mixture falls below the rate of flame propagation, results in a rapid combustion of this mixture which is completed by the necessary excess air entering the chamber 41 through port 40 and uptake 37. This excess air entering through port 40 also directs the flame upon the bath and across the furnace. The amount of air rising up uptake 37 is a function of the opening of the control valve 47 and the thermal head or temperature in the uptake, and this amount is under the control of the furnace operator. Upon reaching the plane of the baffles sufficient air to mix with the fuel in the throat 45 is induced into and through this throat by action 95 of the fuel under pressure. The remainder of the air passes around these baffles and enters the furnace through port 40. This phase of the invention consists in utilizing the induction action of a jet of fuel under pressure 100 for separating the upward flow of air in uptake 37, the required amount of which is forced through the throat 45 by the inductive action of the fuel jet, where an intimate mixture of the fuel and air is obtained. The remainder of the air flowing through uptake 37 enters the furnace through port 40 to complete combustion. In other words, the injection action is not utilized to draw the air up uptake 37, but is utilized for directing 110 the air after it has reached the baffles in the uptake. The air flows up through the uptake 37 as the result of the thermal head or the temperature within said uptake, and the entire energy of the fuel jet is utilized in forming the intimate mixture and inducing the air through throat 45.

In connection with the automatic control of the flow of air up through the air intake 37, the same control mechanism is used, as shown in Figures 1 and 2.

The use of a large uptake permits of an unrestricted flow of waste gases from the combustion chamber down the uptake.

I wish to emphasize the fact that the inducing action of the burner is utilized only to induce through the throat and mix with the fuel, the necessary amount of air to form a combustible mixture and cause a partial com-

bustion within the port, the complete combustion taking place after the induced mixture has passed into the combustion chamber and met the air through the air port 40. The difference in pressure on either side of the port block, that is, in the combustion chamber 41 on one side and the air uptake 37 on the other, is slight, and as the volume of air capable of rising up the uptake 37 is much in excess of the requirements and the amount rising is under the control of the operator, and the amount induced through the throat is constant for each fuel amount and burner setting, the amount of air which passes by the baffles and thence to the furnace is directly under the full control of the furnace operator. Regardless of how much air is passing up the uptake 37, the fluid passing through the throat and the energy necessary to effect such passage is constant for each setting of fuel burner. The induced air is proportionate to the fuel supply.

In reversing this furnace, working on producer gas, there being no gas checkers and chambers necessary, there is no loss of gas contained in them which is wasted to the stack. This amounts to a saving of 3 to 7% of fuel.

In connection with the air intake and the discharge of the products of combustion, the furnace is provided preferably with a single checker or regenerator chamber 50, a settling chamber 51, the slag pocket 36 and uptake 37. In connection with the passage of air, air is drawn in past valve 47 through air checker chamber 50, where the air is heated, whereupon the air passes through settling chamber 51, slag pocket 36 and up through air uptake 37 in the manner hereinabove described. When the furnace is reversed, the products of combustion pass down the uptake 37 through slag pocket 36 where the heaviest particles are deposited and then into settling chamber 51, where less heavy particles are deposited prior to the products of combustion continuing on into the checker chamber 50. In this manner the checkers are prevented from being clogged by relatively heavy material carried with the products of combustion. Upon leaving the air checkers, the products of combustion pass outwardly through a flue 52 leading to a reversing valve, not shown, and the stack, not shown.

While I have shown my invention as applied to an open hearth furnace, it will be understood that it may be applied to furnaces other than open hearth furnaces. For instance, it may be used in connection with large reheating furnaces in steel mill practice for heating billets, slabs and bars preparatory to being rerolled.

There may be various modifications of the invention, and it is my intention to cover all such modifications which do not involve a departure from the spirit and scope of the in-

vention as set forth in the following claims.

I claim:

1. In an open hearth furnace, a port block, an air uptake, and a fuel burner adjustably mounted within said uptake and movable with respect to the port in said port block in accordance with varying conditions. 70

2. In an open hearth furnace, a port block, a baffle located between an end wall of the furnace and the port block, and a fuel burner associated with said baffle and movable with respect to the port in said port block to meet the varying conditions of pressures and kinds of fuel used. 75

3. In an open hearth furnace, a port block, an uptake, means for supplying fuel under pressure to the port in said block for inducing a supply of air from said uptake whereby a combustible mixture of air and fuel and a preliminary combustion takes place within said port, further air from said uptake mixing with the combustible mixture beyond the port for completing combustion of the combustible mixture within the combustion chamber. 80

4. In an open hearth furnace, a port block, an uptake, means for supplying fuel under pressure to the port in said block for inducing a supply of air from said uptake whereby a combustible mixture of air and fuel and a preliminary combustion takes place within said port, and means whereby further air from said uptake mixes with the combustible mixture beyond the port for completing combustion of the combustible mixture within the combustion chamber, said additional air directing the flame onto the bath and through the combustion chamber. 95

5. In an open hearth furnace, a combustion chamber, an uptake for accommodating large volume of flow of products of combustion, means for supplying fuel under pressure for inducing air from said uptake for causing a preliminary combustion prior to passing into the combustion chamber, and means whereby additional air from said uptake enters the combustion chamber to complete combustion and direct the path of the flame. 100

6. In an open hearth furnace, an uptake permitting a large inflow of air into the combustion chamber and a large outflow of products of combustion therefrom, and means for supplying fuel under pressure for inducing a given amount of air from said uptake under given conditions for forming a combustible mixture regardless of the quantity of air flowing through said uptake. 115

7. In an open hearth furnace, an uptake permitting a large inflow of air into the combustion chamber and a large outflow of products of combustion therefrom, means for supplying fuel under pressure for inducing a given amount of air from said uptake under given conditions for forming a combustible mixture regardless of the quantity of air 120

125

130

flowing through said uptake, and a regulating valve for controlling the supply of air passing up the uptake.

8. In an open hearth furnace, an uptake for the passage of air to the combustion chamber and for the passage of products of combustion therefrom, and means for automatically controlling the pressure of the air in the upper part of said air uptake.

9. In an open hearth furnace, a combustion chamber, an uptake through which air may pass to said combustion chamber and through which products of combustion may pass from said combustion chamber, means for supplying fuel under pressure for inducing a given amount of air from said uptake to form a combustible mixture regardless of the amount of air passing through said uptake, and means for automatically controlling the volume of air passing through said uptake.

10. In an open hearth furnace, a combustion chamber, a large volume uptake through which air flows and through which waste gases pass, and means for supplying fuel under pressure for dividing the supply of air passing up the uptake and inducing a portion thereof to form a combustible mixture prior to passing into the combustion chamber, the division of air being made regardless of the area provided for the passage of excess air, the large area provided for excess of air permitting of free passage of waste gases from the furnace to the stack.

11. A furnace provided at each end with air and fuel flues, a separate continuously open discharge at each end operative to conduct products of combustion from the furnace on the outgoing and while admitting substantially no air into the furnace on the incoming end.

Signed at Chicago, Illinois, this 23rd day of November, 1920.

MARCUS C. STEESE.
